(57) CLAIM

The ornamental design for a bra, as shown and described.

DESCRIPTION

FIG. 1 is a front view of a bra according to the design; FIG. 2 is a rear view thereof;

FIG. 3 is a left side view thereof;

FIG. 4 is a right side view thereof;

FIG. 5 is a front perspective view thereof;

FIG. 6 is a rear perspective view thereof; and,

FIG. 7 is a rear environmental view thereof.

The broken line showing of the arms, torso, neck, and head in FIG. 7 is for the purpose of illustrating portions of the environmental structure and forms no part of the claimed design.

1 Claim, 7 Drawing Sheets
